UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

PNEUMATIC VALVE ACTION.

Application filed May 12, 1924. Serial No. 712,521.

This invention relates to pneumatic valve actions for automatic musical instruments and has as one of its objects the provision of an improved pneumatic structure, and 5 method of making the same.

Other and more specific objects and advantages of the invention will appear hereinafter.

A preferred embodiment of the invention 10 selected for purposes of illustration is shown in the accompanying drawings, in which,

Figure 1 is a sectional view of a valve action embodying the invention.

Figure 2 is a similar view showing the 15 parts as they appear when operated,

Figures 3, 4, 5 and 6 are semi-diagrammatic views showing the method of making the pouch structure illustrated in Figures 1 and 2,

Figure 7 is a view of the assembled pouch 20 previous to insertion in the valve action shown in Figures 1 and 2,

Figure 8 is an inverted plan view of the assembled pouch with the membrane flattened out as in use.

25 Referring to the drawings, the invention has been illustrated as applied to a pneumatic valve action of the outside valve type, although as will appear to those skilled in the art it is susceptible of application to specific structures other than that illustrated herein.

In the drawings an exhaust chest 1 is illustrated, formed between the parallel boards 2 and 3 which are separated by suitable strips 4. The upper board 2 is provided with a 30 valve port 5 with which the valve 6 is adapted to cooperate, the upper and lower faces of the board 2 serving as valve seats. The valve heads may be faced with disks of leather or other suitable material 7 to insure air-tight 35 contact. The upper board 2 is also provided with a passage 8 communicating with the port 5 through which a suitable pneumatic device may be connected to either atmosphere or exhaust under control of the valve 6 for actuation in the usual manner.

Instead of the usual diaphragm for actuating the valve 6, the apparatus of the present invention is provided with a pouch 10 of thin, light, flexible material such as very thin 40 intestinal membrane. In the preferred form of the invention the thickness of this material should not substantially exceed a few thousandths of an inch, and it has been found that material only one thousandth of an inch 45 in thickness may be used successfully. Mem-

brane of this description is characterized by extreme lightness and flexibility and operates almost without inertia or internal friction, and is, therefore, an extremely desirable material for use in valve actions. It was 60 found, however, that heat and cold and various conditions of atmospheric moisture sometimes caused the material to stretch and contract to a much greater extent than the materials ordinarily used for diaphragms. For 65 this reason it was found inadvisable to use such thin material in the customary diaphragm form in many valve actions.

The pouch form of actuating device illustrated provides a means by which the membrane previously described can be successfully used, for, as will be apparent, considerable shrinkage or expansion can occur without affecting the operation of the valve materially. It will be apparent, however, that 70 the pouch form of actuating device may be advantageously formed of material other than that specifically described above. Quite apart from the material of which the pouch is formed, the pouch shape is found to operate more quickly and surely than the usual diaphragm, even when formed of the thicker material of which it is customary to make 75 diaphragms.

In order to hold the membrane tightly, a 80 pair of collars 12 and 13 have been provided between which the edges of the pouch are held, the whole structure being sunk into a recess 14 formed in the board 3. A small 85 groove 15 is also formed in the board 3 surrounding the collar 13 which may be filled with glue or shellac to hold the collars firmly 90 in place and to form a seal to prevent leakage.

The outer collar 13 may be conveniently 95 made of metal, while the inner may be formed of wood. Passage 16 is provided in the collar 12 through which atmospheric air may be admitted to the pouch 10 to actuate the valve in the usual manner. A bleed 17 is provided to maintain the pouch and passage 16 and the 100 tube 18 to a tracker bar or other controlling devices normally under exhaust from the exhaust chest 1.

In assembling the structure described 105 above, a board 25 may be employed having a recess 26 formed therein of the same size as the recess 14 formed in the board 3. The board 25 may also be provided with an opening 27, the purpose of which will appear hereinafter. In assembling, one of the collars 13 110

of the type previously described is coated on its inner sides with glue and placed in the recess 26 as illustrated in Figure 3 and the membrane 10 or other material, of which the pouch is to be formed, is laid over the recess 26 on top of the board 25. A board 28 is then laid over the board 25 with its cone-shaped opening 29 over the recess 26. The board 28 is held with some pressure so that when the mandrel 30 illustrated in Figure 4 is pushed downwardly as illustrated in Figure 5, the membrane will be drawn evenly from all sides. As will be apparent, this will result in a folding or crimping of the membrane as it is drawn through the collar 13 and the opening 27. The mandrel may then be removed and the collar 12, which has previously been coated with glue or shellac on its outer side, may be pressed into the depression to hold the membrane firmly in place. The assembled collars and membrane may then be removed from the board 25 and is ready for insertion in the depression 14 in the board 3 after the surplus ends of the material have been trimmed.

The operation of the device is similar to a valve action of the standard type. The chest 1 is maintained under suitable exhaust and the pouch 10 and passages 16 and 18 are also maintained under exhaust through the bleed 17. Since the pressures are thus equalized, the valve 6 remains in its lowered position as illustrated in Figure 1. If atmospheric air is admitted under these conditions to the passage 18 from a tracker bar or other mechanism, the pressures are unbalanced and the pouch 10 is inflated to raise the valve 6 in the usual manner. As soon as the passage 18 is closed to atmospheric air, the pressures again become equalized and the valve 6 drops to its original position.

It is to be understood that the invention may be variously modified and embodied within the scope of the subjoined claims.

45 I claim as my invention:

1. In a pneumatic valve action, in combination, a valve, and means to actuate said valve, including a member of flexible material, a board to which said member is secured, said member being folded above said board to form a cap-shaped pouch, the diameter of said member being substantially less at the point where secured to said board than the diameter of said folded portion 55 above the board.

2. A pouch for a pneumatic valve action comprising a sheet of thin flexible material pronouncedly constricted at its point of attachment to said action and bulging outwardly from said point of attachment, and upwardly and inwardly over said point. 60

3. In a pneumatic valve action, in combination, a valve, a pouch to actuate said valve, a board, a pair of collars having diameters less than the diameter of said pouch between 65 which the edges of said pouch are held, said board being provided with a recess into which said collars fit, and one of said collars and said board being provided with passages through which air may be admitted to said pouch. 70

4. A pouch for a pneumatic valve action comprising a sheet of thin flexible material puckered to a size smaller than its outside diameter, said puckered portion being secured 75 between a pair of cooperating members.

5. A pouch for a pneumatic valve action of thin flexible material and formed with a pronouncedly constricted neck portion through which air may be admitted and a 80 bag portion of substantially greater diameter than said neck portion.

6. A pouch for a pneumatic valve action formed of a sheet of thin flexible material having its edges puckered and having a bag 85 portion of greater diameter than said puckered portion.

7. The method of making pneumatic valve pouches from a sheet of flexible material which includes inserting the central portion 90 of said sheet through a substantially cylindrical collar while frictionally restraining the edges thereof, withdrawing the inserting means, and inserting a second collar within the first collar to hold the pouch in position. 95

8. In a pneumatic valve action, in combination, a valve, and means to actuate said valve, including a pouch of intestinal membrane having a thickness of less than two thousandths (2/1000) of an inch. 100

9. In a pneumatic valve action, in combination, a valve, and means to actuate said valve, including a pouch of flexible material having a thickness of less than five thousandths (5/1000) of an inch. 105

In testimony whereof, I have signed my name to this specification this 8th day of May, 1924.

CHARLES F. STODDARD.
